UNITED STATES PATENT OFFICE

112,585

DESIGN FOR A HAT

Herman Freyberg, New York, N. Y.

Application April 22, 1938, Serial No. 76,706

Term of patent 3½ years

To all whom it may concern:

Be it known that I, Herman Freyberg, residing at New York, in the county of New York and State of New York, have invented a new, original, and ornamental Design for a Hat, of which the following is a specification, reference being had to the accompanying drawing, forming a part thereof.

The design comprises a brim portion, narrow in back and relatively wider in front, the inside of said brim being edged with pointed open-work

trimming forming the crown portion of the hat, and the outside of the brim being edged with matching trimming, as shown.

Figure 1 is a front elevational view showing my new design;

Figure 2 is a fragmentary plan view of the hat shown in Figure 1.

I claim:

The ornamental design for a hat, as shown and described.

HERMAN FREYDBERG.
